[57]

CLAIM

The ornamental design for a table or similar article, as shown and described.

DESCRIPTION

FIG. 1 is a perspective view of a table or similar article showing my new design;

FIG. 2 is a side elevational view;

FIG. 3 is a top plan view;

FIG. 4 is an end view; and

FIG. 5 is a bottom plan view thereof.

The side and end not shown are mirror images of the side and end shown respectively.
